OTTO A. KREUTZBERG, OF LAKE BLUFF, ILLINOIS, ASSIGNOR TO KREUTZBERG METER COMPANY, OF CHICAGO, ILLINOIS, A CORPORATION OF ILLINOIS.

HEATER FOR MOTOR FLUIDS.

1,170,976.

Specification of Letters Patent.

Patented Feb. 8, 1916.

Application filed March 7, 1914, Serial No. 823,102. Renewed June 23, 1915. Serial No. 35,939.

To all whom it may concern:

Be it known that I, OTTO A. KREUTZBERG, a citizen of the United States, residing at Lake Bluff, in the county of Lake and State of Illinois, have invented a new and useful Improvement in Heaters for Motor Fluids, of which the following is a specification.

My invention relates to improvements in heaters for motor fluids, and more particularly to the type of heaters illustrated and described in U. S. Letters Patent No. 1,020,067, granted to M. C. White and O. C. Duryea, March 12, 1912, though it is not my intention to limit my invention to use in connection with this type of heaters.

Considerable difficulty has been experienced in the operation of heaters as hitherto provided due to the fact that the burners therein, which are subjected to the motor fluid in its passage from the source of supply to the point of use, did not produce perfect combustion of the oil which caused large quantities of free carbon to be released, and precluded the successful operation of the device.

My primary objects are to provide a construction of heater which shall operate to produce perfect combustion of the oil, causing it to burn with a blue flame and thereby preventing the formation of free carbon; and to provide against the flashing-back of the flame and burning as a yellow flame, when the flow of motor-fluid through the heater is arrested.

Referring to the accompanying drawings, Figure 1 is a view in vertical sectional elevation of a heater constructed in accordance with my invention. Fig. 2 is an enlarged view in vertical sectional elevation of the burner of my improved heater; and Fig. 3, a plan view of the burner of Fig. 2.

As the heater in connection with which I have chosen to illustrate my invention is of the same general construction as that illustrated and described in the U. S. Letters Patent above referred to, a general description only of the general construction of the heater illustrated, will suffice.

The heater is formed with a central inverted U-shaped conduit 4 for the passage of the motor-fluid, as, for example, compressed air therethrough, this conduit extending at opposite sides of and across the upper open end of a combustion chamber

5, into which my improved burner construction hereinafter described, extends, the conduit 4 being surrounded by an annular chamber 6, which, in practice, would preferably be packed with asbestos indicated at 7. One end of the conduit 4 opens into a chamber 8 containing a valve 9, preferably in the form of an unguided disk, adapted to loosely fit a seat 10 provided in the wall of a passage 11 opening into the chamber 8 from a chamber 12 in communication with the pipe 13 leading from the supply (not shown) of compressed motor-fluid. The valve 9 is backed by a coiled spring 14 which abuts against a plug 15 in the casing of the heater, this spring being of such tension that it will yield, to permit the valve 9 to open, under a relatively low drop of pressure of the motor-fluid in the conduit 4, as compared with the pressure in the chamber 12, as, for example, where the motor-fluid is supplied from the pipe 13 at one-hundred pounds pressure, a drop of the pressure in the conduit 4 to ninety-nine and one-half pounds will cause the valve 9 to open. The oil, which may be gasoline, kerosene, or any other suitable fuel oil is contained in a chamber 16, and is supplied to the burner of the heater in a manner hereinafter described.

The form in which I prefer to provide my improved burner is that illustrated, a description of which is as follows: The bottom and top walls of the chamber 16 are provided with openings 17 and 18, respectively, into which the casing 19 of the burner at its enlarged threaded and tapered portions 20 and 21, respectively, closely fits, the upper end of the casing extending upwardly into the lower end of the combustion chamber 5, a gasket 19^a being confined between the casing 19 and the wall of the chamber 5 to provide an air-tight joint. The casing 19 contains a tube 22 extending longitudinally of this casing and spaced therefrom at those portions of the casing which extend between the under surface of the upper wall of the chamber 16 and the bottom wall thereof, and above the upper surface of the upper wall of the chamber 16, thus providing non-communicating upper and lower annular chambers 23 and 24, respectively, between the casing 19 and the tube 22. The casing 19, adjacent to the bottom of the chamber 16, con-

tains an opening 25 equipped with a screen 26 affording communication between the chamber 16 and the chamber 24, a vent 27 being provided in the casing 19 adjacent to 5 the top wall of the chamber 16. The annular chamber 24 communicates with the interior of the tube 22 through openings 28, whereby the oil in the chamber 16 is caused to enter the tube 22. The portion of the casing 19 located in the chamber 12 contains 10 screened openings 29, affording communication between the chamber 12 and the chamber 23. The upper end of the casing 19 is provided with a plug 30 containing in its 15 under side a downwardly flaring recess 31 of general conical shape which communicates with an opening 32 in this plug, the upper end 33 of the tube 22 being of conical form, as illustrated, to conform generally to 20 the contour of the recess 31 and containing an aperture 34 in line with the opening 32 and communicating with the interior of the tube 22. The inner surface of the upper end wall of the tube 22 is of conical form and 25 coöperating with this surface is the upper conical end 35 of a valve-rod 36 which extends longitudinally of the tube 22, spaced therefrom as illustrated, the lower end of this rod having screw connection, as indicated at 37, with a plug 38 screwed into the 30 plug 20, this rod being equipped with a handle portion 39, whereby it may be rotated for moving it longitudinally in the tube 22, thereby adjusting the conical end 35 of this 35 rod toward and away from the inner conical surface of the tube 22 for controlling the amount of oil discharged through the opening 34 as hereinafter described.

The oil is forced from the chamber 16 into 40 the tube 22 and out through the opening 34 by means of the difference in air-pressure in the conduit 4 and the chambers 12 and 16, this being accomplished in the same manner as disclosed in said U. S. Letters Patent, 45 namely, by providing communication, as by means of a tubular device (not shown) opening at one end into the chamber 12 and at its opposite end into the chamber 16, it being readily understood that as the pressure in 50 the conduit 4 does not, during the passage of motor-fluid therethrough, quite equal the pressure in the chamber 12, oil in the chamber 16 will be forced by the pressure of the motor-fluid therein up into the passage 34 in 55 the tube 22.

The air for mixture with the oil supplied to the tube 22, as stated, enters the chamber 23 from the chamber 12 and flows out through the upper apertured end of the 60 latter mixing with the oil from the opening 34.

Extending above the nozzle thus provided by the plug 30 and tube 22, is a burner head 40 which preferably is of metal and which, 65 in the construction shown, is provided at its

lower end with a ring-flange 41 at which it is screwed upon the upper end of the casing 19. The burner-head 40, which is provided for the purpose of receiving the air and oil as it issues from the nozzle, is provided with 70 a longitudinally-extending passage 41 with which upwardly-inclined branch-passages 42, opening through the outer surface of the head 40, communicate at their lower ends, these branch-passages being preferably arranged in vertical series, as illustrated, and the passage 41 being preferably slightly tapered upwardly from a point adjacent to that at which the lowermost series of branch-passages 42 open thereinto, it being preferred 75 that the passage 41 at points coincident with the various branch-passages 42 be of cross-sectional areas approximately directly proportionate to the combined areas of the branch-passages at said points of coincidence and all of those branch-passages beyond such points for causing streams of 80 gas to issue from these branch-passages at substantially uniform velocity, thus producing jets of flame at each of said branch-passages of substantially the same length. 85

It is necessary in an apparatus of the character to which this invention relates that not only should the formation of free carbon be prevented, but provision should 90 be made for preventing the flashing back of the flame into the burner, which would cause the fuel to burn with a yellow flame, when the flow of motor fluid through the apparatus and the consequent flow of air to the 95 nozzle of the burner for combustion purposes, is arrested. Accordingly, it is necessary that not only should the oil and air be thoroughly mixed, but the mixture thus produced should be gasified before ignition. In 100 this connection, the construction of the burner-head 40 is of great importance. Theoretically, the combined cross-sectional areas of the branch-passages 42, where the 105 velocity of the mixed oil and air supplied to the passage 41 is produced by relatively low pressure, say about one-half pound, which is usually the case in apparatus of this character, should not be greater than the cross-sectional area of the passage 41 110 below the lowermost branch-passages 42. It is well known, however, that gas in passing under pressure through an aperture flows 115 therethrough in a stream of less cross-sectional area than the cross-sectional area of the interior of the passage. Thus in practice, where the pressure of the mixed oil and air is relatively low, the branch-passages 42 should be provided of such number and of such diameter, or diameters, that the 120 combined cross-sectional areas of the streams of gas, at their smallest sections, passing through the branch passages 42, shall not be greater than the cross-sectional area of the stream of gas in the main feed-passage 125 130

41 below the point at which the lowermost series of passages 42 open into this main passage, and the length of each passage 42, relative to its diameter, should be such as to cause the flame to be smothered therein when the velocity of the gas through said branch-passages is less than the velocity of combustion against the flow of gas through said branch-passages, viz., each branch-passage 42 at least approximately four times its diameter. By so forming the burner, the flashing-back of the flame into the passage 41, during the normal operation of the heater, is prevented, as the velocity of the flow of gas through the passages 42 will exceed the velocity of combustion against this flow, and the flashing back of the flame into the passage 41, when the velocity is reduced to practically zero, is prevented by reason 20 of the relative length of each passage 42 to its diameter, which causes the flame to smother at the outer ends of these branch-passages.

In starting the burner, when cold, the oil 25 vaporized by the air in passing from the nozzle through the branch-passages 42 condenses on, and flows down, the outer side of the burner-head 40 collecting on the wick 43 of absorbent material, as, for example, asbestos, encircling the lower portion of the head 40. The oil thus collected is then ignited in any suitable manner, as, for example, by an electric sparking means, not shown, which would be located closely adjacent to the wick 43, as shown in the said U. S. patent. The burning of the oil on the wick 43 heats the head 40, and as soon as the temperature of the latter has risen to a certain point, the mixed air and vaporized oil become changed in a fixed gas igniting at the outer ends of the passages 42 and burning with an intensely hot blue flame which serves to heat to a high degree the compressed motor-fluid passing through the conduit 4.

The provision of the passages 42 as upwardly-inclined passages is of importance as the jets of flame which issue therefrom do not reach the inner surface of the combustion chamber 5, thus permitting air to flow from the upper end of the chamber 5 downwardly along its inner wall to aid in supporting combustion.

It will thus be understood from the foregoing description that my improved burner provides, not only for the thorough mixing of the air and oil, but also for the production of a fixed gas which burns at all times during the supply of the fuel to the burner, with a clean blue flame, and when the flow of gas from the heater is arrested, the flame at the burner, instead of flashing back into the burner and burning therein, which would produce a yellow flame and consequently free carbon, immediately becomes

extinguished at the outer ends of the passages 42.

While I have illustrated and described a particular embodiment of my invention, I do not wish to be understood as intending to limit it thereto, as the same may be variously modified and altered without departing from the spirit of my invention, it being my intention to claim my invention as broadly and completely as the prior state of the art will permit.

What I claim as new and desire to secure by Letters Patent is:

1. In a heater for the purpose set forth, the combination of a source of compressed air, a conduit for conveying the compressed air to the point of use, a burner exposed to the air in said conduit and formed of a gasifying head, a supply of fuel-oil, and means for supplying a mixture of air under a pressure exceeding that of the air in said conduit when air is flowing therefrom to the point of use, and oil from said oil supply, into said burner-head.

2. In a heater for the purpose set forth, the combination of a source of compressed air, a conduit for conveying the compressed air to the point of use, a burner exposed to the air in said conduit and formed of a burner-head provided with a main passage and branch passages opening into said main passage, and means for supplying a mixture of air under a pressure exceeding that of the air in said conduit when air is flowing therefrom to the point of use, and oil, to said main passage, the length of said branch passages relative to their diameters being such as to cause the jets of flame issuing therefrom to be smothered therein when the velocity of the gas through said burner passages is less than the velocity of combustion against the flow of gas through said branch passages.

3. In a heater for the purpose set forth, the combination of a source of compressed air, a conduit for conveying the compressed air to the point of use, a burner exposed to the air in said conduit and formed of a burner-head provided with a main feed-passage and branch passages opening into said main passage, and means for supplying a mixture of air under a pressure exceeding that of the air in said conduit when air is flowing therefrom to the point of use, and oil, to said main passage, said main and branch passages being so proportioned that the combined cross-sectional areas of the streams of fuel passing through said branch passages, at their smallest cross-sections, shall not be greater than the cross-sectional area of the stream of fuel in said main passage adjacent to the lowermost branch passages.

4. In a heater for the purpose set forth, the combination of a source of compressed

- air, a conduit for conveying the compressed air to the point of use, a burner exposed to the air in said conduit and formed of a burner-head provided with a main passage and branch passages opening into said main passage, and means for supplying a mixture of air under a pressure exceeding that of the air in said conduit when air is flowing therefrom to the point of use, and oil, to said main passage, said main and branch passages being so proportioned that the combined cross-sectional areas of the streams of fuel, passing through said branch passages, at their smallest cross-sections, shall not be greater than the cross-sectional area of the stream of fuel in said main passage adjacent to the lowermost branch passages, the length of said branch passages relative to their diameters being such as to cause the jets of flame issuing therefrom to be smothered therein when the velocity of the gas through said branch passages is less than the velocity of combustion against the flow of gas through said branch passages.

5. In a heater for the purpose set forth, the combination of a source of compressed air, a conduit for conveying the compressed air to the point of use, a burner exposed to the air in said conduit and formed of a burner-head provided with a main passage and branch passages opening into said main passage, and upwardly-inclined branch passages opening into said main passage, and means for supplying a mixture of air under a pressure exceeding that of the air in said conduit when air is flowing therefrom to the point of use, and oil, to said main passage, said main and branch passages being so proportioned that the combined cross-sectional areas of the streams of fuel, passing through said branch-passages, at their smallest cross-sections, shall not be greater than the cross-sectional area of the lowermost branch passages.

6. In a heater for the purpose set forth, the combination of a source of compressed air, a conduit for conveying the compressed air to the point of use, a burner exposed to the air in said conduit and formed of a burner-head provided with a main feed-passage and branch passages opening into said main passage, and upwardly-inclined branch passages opening into said main passage, and means for supplying a mixture of air under a pressure exceeding that of the air in said conduit when air is flowing therefrom to the point of use, and oil, to said main passage, the length of said branch passages relative to their diameters being such as to cause the jets of flame issuing therefrom to be smothered therein when the velocity of the gas through said branch passages is less than the velocity of combustion against the flow of gas through said branch passages.

7. In a heater for the purpose set forth, the combination of a source of compressed air, a conduit for conveying the compressed air to the point of use, a burner exposed to the air in said conduit and formed of a burner-head provided with a main feed-passage and branch passages opening into said main passage, and upwardly-inclined branch passages opening into said main passage, and means for supplying a mixture of air under a pressure exceeding that of the air in said conduit when air is flowing therefrom to the point of use, and oil, to said main passage, said main and branch passages being so proportioned that the combined cross-sectional areas of the stream of fuel, passing through said branch-passages, at their smallest cross sections, shall not be greater than the cross-sectional area of the stream of fuel in said main passage adjacent to the lowermost branch passages, the length of said branch passages relative to their diameter being such as to cause the jets of flame issuing therefrom to be smothered therein when the velocity of the gas through said branch passages is less than the velocity of combustion against the flow of gas through said branch passages.

8. In a heater for the purpose set forth, the combination of a source of compressed air, a conduit for conveying the compressed air to the point of use, a burner exposed to the air in said conduit and formed of a burner-head provided with a main feed-passage and branch passages opening into said main passage, and means for supplying a mixture of air under a pressure exceeding that of the air in said conduit when air is flowing therefrom to the point of use, and oil, to said main passage, said main passage at points coincident with said branch passages being of such cross-sectional areas approximately directly proportionate to the combined areas of said branch passages at said points of coincidence and all of those branch passages beyond such points.

9. In a heater for the purpose set forth, the combination of a source of compressed air, a conduit for conveying the compressed air to the point of use, a burner exposed to the air in said conduit and formed of a gasifying burner-head containing a main passage and branch passages opening into the latter, a supply of fuel-oil, and means for supplying a mixture of air under a pressure exceeding that of the air in said conduit when air is flowing therefrom to the point of use, and oil from said oil supply, into said burner-head.

10. In a heater for the purpose set forth, the combination of a source of compressed air, a conduit for conveying the compressed air to the point of use, a burner exposed to the air in said conduit and formed of a gasifying burner-head containing a main pas-

sage, and upwardly-inclined branch passages opening into said main passage, and means for supplying a mixture of air under a pressure exceeding that of the air in said conduit when air is flowing therefrom to the point of use, and oil, to said main passage.

11. In a heater for the purpose set forth, the combination of a source of compressed air, a conduit for the compressed air communicating with said supply, a differential valve controlling the flow of fluid into said conduit, a pipe connected with said conduit for conveying the compressed air to the point of use, a burner exposed to the air in

said conduit and formed of a gasifying 15 burner-head containing a main passage and branch-passages opening into the latter, a supply of fuel-oil, and means for supplying a mixture of air under a pressure exceeding that of the air in said conduit when air is 20 flowing therefrom to the point of use, and oil from said oil supply, into said burner-head.
